UNITED STATES PATENT OFFICE.

GILBERT COURRAULT, OF PARIS, FRANCE, ASSIGNOR TO BOURJOIS, INC., OF NEW YORK, N. Y., A CORPORATION OF NEW YORK.

DESIGN FOR A LID FOR A VANITY CASE OR A SIMILAR ARTICLE.

Application filed February 17, 1928, Serial No. 25,469, and in France October 29, 1927. Term of patent 14 years.

To all whom it may concern:

Be it known that I, GILBERT COURRAULT, a citizen of the Republic of France, residing at Paris, France, have invented a new, original, and ornamental Design for a Lid for a Vanity Case or a Similar Article, of which the following is a specification, reference being made to the accompanying drawings, forming a part thereof.

Fig. 1 is a top plan view of a lid for a

vanity case or similar article showing my new design, and Fig. 2 is an edge view thereof.

The dominating feature of the present design is the ornamentation on the top.

I claim:

The ornamental design for a lid for a vanity case or a similar article substantially as shown and described.

GILBERT COURRAULT.
